UNITED STATES PATENT OFFICE.

CHARLES LE G. FORTESCUE, OF WILKINSBURG, PENNSYLVANIA, ASSIGNOR TO
WESTINGHOUSE ELECTRIC & MANUFACTURING COMPANY, A CORPORATION
OF PENNSYLVANIA.

MULTIPLE-RATIO TRANSFORMER.

No. 879,252.

Specification of Letters Patent.

Patented Feb. 18, 1908.

Application filed June 8, 1907. Serial No. 378,014.

To all whom it may concern:

Be it known that I, CHARLES LE G. FORTESCUE, a subject of the King of Great Britain, and a resident of Wilkinsburg, in the county of Allegheny and State of Pennsylvania, have invented a new and useful Improvement in Multiple-Ratio Transformers, of which the following is a specification.

My invention relates to electrical transformers, and it has for its object to so arrange the winding of a transformer and the connection thereof as to provide for a large number of ratios between the voltages of the primary and secondary windings, and so that adjustment of the voltage ratio may be effected without unbalancing the magnetic circuits, or materially affecting the inductance and the power factor of the transformer.

In electrical transformers, it is desirable that the primary and secondary windings be so disposed with reference to each other that there may be a maximum degree of interlinking and substantial neutralization of the fluxes corresponding thereto, and, to this end, the windings are usually divided into a plurality of sections that are interpolated close together in a symmetrical arrangement. Also, in order that a variety of voltages may be obtained from the same transformer, the windings are usually provided with a plurality of leads, whereby the active lengths thereof may be adjusted, but, as transformers have been constructed heretofore, the leads have been connected to the windings at such points that the distances between the active portions of the windings have been increased upon removing portions thereof, thereby increasing the leakage and the inductance in the transformer.

The symmetrical arrangement of the active portions of the windings has sometimes been interfered with also, when effecting voltage adjustment and a relatively large number of leads has been necessary in order to obtain a large variety of voltages. In the present transformer, however, the leads are so arranged that the distances between the active portions of the respective windings remain constant when removing portions thereof for the purpose of effecting voltage adjustment, so that the inductance of the transformer remains substantially the same for all voltages. The symmetrical arrange-

ment of the windings is also not materially disturbed, so that there is little or no tendency toward unbalancing of the fluxes in corresponding portions of the magnetic circuit, and a large number of voltages may be obtained by employing a relatively small number of leads.

Figure 1, of the accompanying drawings, is a diagrammatic view of a portion of a transformer that embodies my invention, and Figs. 2 to 18, inclusive, are diagrammatic views illustrating the modes of connecting the windings to obtain a plurality of voltage ratios in the transformer.

In Fig. 1, a portion of the core or magnetic circuit 1 of a transformer is provided with a plurality of coils 2 to 21, inclusive, coils 2, 8, 15, and 21 constituting as many sections of the low voltage winding of the transformer, and the remaining coils being divided into three groups constituting three sections of the high voltage winding. It will be observed that each of the two outer sections of the high voltage windings comprises five coils while the middle group comprises six coils, and that the interpolation of the section belonging to the respective windings is such as to form a symmetrical arrangement in order to insure, as far as possible, a balance of the fluxes in corresponding portions of the magnetic circuit. The extremities of the high voltage winding are connected, respectively, by means of leads 22 and 23, to terminals 24 and 25 upon a terminal board or block 26, the terminals 24 and 25 being connected, when the transformer is in use, to a suitable external circuit (not shown). The high voltage winding comprises two parts of equal length that may be connected either in series or parallel arrangement, the inner extremities 27 and 28; i. e., the terminals of the coils 11 and 12, being connected, respectively, to terminals 29 and 30 on the terminal block 26.

In order to provide means for effecting adjustment of the voltage of the winding, suitable points in the coils 10 and 13 are connected, respectively, by means of leads 31 and 32 to terminals 33 and 34 upon the terminal board 26. For this purpose, also, extremities of the coils 5 and 6 are connected, respectively, to terminals 35 and 36 upon an auxiliary terminal block 37; and suitable points of the said coils are connected, respec-

tively, to terminals 38 and 39, also upon the terminal block 37, while extremities of coils 17 and 18 are connected, respectively, to terminals 40 and 41 upon another auxiliary terminal block 42, and suitable points in the said coils are connected, respectively, to terminals 43 and 44 upon the terminal block 42.

In order to understand the operation of the invention reference should be had to Figs. 2 to 18, inclusive, in which are illustrated the connections of the leads to the high voltage winding for obtaining a variety of voltages.

In Fig. 2 terminals 29 and 30 are connected together, also, as are terminals 35 and 36, and terminals 40 and 41, all of the high voltage winding being then in series and the voltage of the winding being the highest obtainable.

In Fig. 3, the connections remain the same except that terminal 35 is connected to terminal 39 instead of to terminal 36, a section of the coil 6 being thereby removed from the circuit and the voltage of the winding being correspondingly reduced.

In Fig. 4, terminal 41 is connected to terminal 43, the connections otherwise remaining the same as in Fig. 3. A portion of the coils 17 is then excluded from the circuit and the voltage of the winding is again correspondingly reduced.

In Fig. 5, terminals 36 and 38 are connected together, the remaining connections being as in Fig. 4, and a section of each of coils 5 and 17 being thus removed from circuit. It will then be seen from Fig. 1 that the portion of the coil 5 included between terminals 35 and 38 is of greater length than the portion of the coil 6 included between terminals 36 and 39, and that the portion of the coil 18 included between terminals 41 and 44 is of greater length than the portion of the coil 17 included between terminals 40 and 43. In order that successive steps in voltage may be provided, the portions of the coils 5 and 18 that may be removed from circuit should be, respectively, of twice the active length of the parts of the coils 6 and 17 that may be removed from the circuit. Thus, it will be understood that with the connections of Fig. 5, a lower voltage is obtained than with the connections of Fig. 4.

In Fig. 6 portions of the coils 5 and 18 are excluded from the circuit since terminals 40 and 44 are connected together, and in Figs. 7 and 8 portions of the coils 6 and 17 are also respectively excluded from the circuit, since, in Fig. 7, terminals 38 and 39 are connected together while, in Fig. 8, terminals 43 and 44 are connected together, corresponding reductions in the voltage being thus effected.

In Fig. 9 terminals 30 and 33 upon the terminal block 26 are connected together, as are also terminals 38 and 39 upon the block 37, and terminals 40 and 44 upon the block

42, portions of the coils 5, 6, 10, and 18 and all of the coil 11 being thereby excluded from the circuit. Another reduction in the voltage equal to the previous reductions will thus occur if the portion of the winding included between terminals 29 and 33 is equal to the portion of the coil 5 that is included between the terminals 35 and 38. For a like reason, the portion of the winding included between terminals 30 and 34 should also be equal to the portion of the coil 5 included between terminals 35 and 38.

In Fig. 10, a portion of the coil 17 is excluded from the circuit, in Fig. 11, portions of the coils 5, 6, 10, 13, and 18 and all of coils 11 and 12 are excluded from the circuit, and in Fig. 12, a portion of the coil 17 is excluded from the circuit, equal reductions in the voltage being thus effected.

In Fig. 13, terminals 24 and 30 are connected together as are also terminals 25 and 29, terminals 35 and 36, and terminals 40 and 41, the portions of the winding included, respectively, between terminals 24 and 29 and between terminals 25 and 30 being thus connected in parallel relation.

In Fig. 14, the sections of the windings 6 and 17 are removed from the circuit, in Fig. 15, sections 5 and 18 are removed from the circuit, and in Fig. 16, portions of each of coils 5, 6, 17, and 18 are removed from the circuit, corresponding equal reductions in the voltage being effected by the connections represented by the respective figures.

In Fig. 17, sections of each of coils 5, 10, 13, and 18 and all of coils 11 and 12 are removed from the circuit, while, in Fig. 18, portions of coils 6 and 17 are also removed from the circuit.

It should be noted that the leads, whereby portions of the high voltage winding are removed from the circuit in order to effect adjustment of the voltage of the transformer, are connected at or near the middle points of the three sections of the high voltage winding, and to the coils that are located approximately midway between the coils or sections of the low voltage windings. Thus, the portions of the high voltage winding that are removed from the circuit when effecting voltage adjustment are located farthest from the coils of the other winding and, consequently, in the weakest leakage magnetic field thereof. Inasmuch as the symmetrical arrangement with respect to each other of the primary and secondary windings remains substantially undisturbed, there is very little tendency toward unbalancing of the fluxes in corresponding portions of the magnetic circuit. The inductance and power factor of the transformer, therefore, remain unaltered in any substantial degree during adjustment of the voltage of the transformer. A large number of voltages is also obtained by the use of a smaller

125
130

number of leads than in previous arrangements of the connections.

I claim as my invention:

1. In a transformer, the combination with primary and secondary windings comprising a plurality of sections, the sections of each winding being interpolated with those of the other in a symmetrical arrangement, of means for removing portions of the sections 10 of one winding that are located in the weakest leakage magnetic field of the other winding.

2. In a transformer, the combination with primary and secondary windings comprising 15 a plurality of sections, the sections of each winding being interpolated with those of the other in a symmetrical arrangement, of means for removing from the circuit portions 20 of the sections of one of the windings that are located approximately midway between the sections of the other windings.

3. In a transformer, the combination with primary and secondary windings, of means 25 for varying the active length of a portion of one of the windings that is located in the weakest leakage magnetic field of the other winding.

4. In a transformer, the combination with a winding comprising a plurality of sections, 30 and another winding located between the sections thereof, of means for adjusting the active length of that portion of the latter winding which is located approximately midway between the sections of the former.

5. In a transformer, the combination with 35 a winding comprising a plurality of sections, and another winding located between the sections thereof, of a plurality of leads connected to that portion of the latter winding which is located approximately midway between the sections of the former, and means for connecting different pairs of said leads to adjust the voltage ratio of the transformer. 40

6. In a transformer, the combination with a winding comprising a plurality of sections, 45 and another winding located between the sections thereof, of a plurality of leads connected to that portion of the latter winding which is located in the weakest leakage magnetic field between the sections of the former winding, and means for connecting different 50 pairs of said leads to adjust the voltage ratio of the transformer.

7. In a transformer, the combination with a winding comprising a plurality of sections, 55 and another winding located between the sections thereof, of means for adjusting the active length of that portion of the latter winding which occupies the weakest leakage magnetic field between the sections of the former. 60

In testimony whereof, I have hereunto subscribed my name this 31st day of May, 1907.

CHARLES I.E. G. FORTESCUE.
